UNITED STATES PATENT OFFICE.

HERMAN BIELEFELDT, OF BERLIN, GERMANY.

DEVICE FOR PRODUCING OFFSET PRINTS.

Application filed February 14, 1925, Serial No. 9,270, and in Germany February 23, 1924.

My invention relates to a cylinder printing machine on which two-colour offset printing, or two-colour book and offset printing, or one colour book, or one colour offset printing, can be produced, and on which the transfers required for the preparation of the offset printing can be produced on zinc or aluminum plates according to a considerably simplified transfer process with 10 complete elimination of reversals and needling or sticking up.

In order to prepare for the offset printing according to this invention, I take a proof on a sheet of suitable paper, this proof being 15 a positive or right-sided one. I now turn over or reverse this right-sided proof by pressing it onto a suitable transfer material and from this material I transfer the print right side up to the zinc or aluminum plate 20 to be mounted on the plate cylinder of a printing press. After the usual preparation of this plate printing can be proceeded with at once and a one-colour offset print is obtained in this manner.

25 If plates are to be prepared for two-colour offset printing, two proofs are made, for instance from the type or printing forme of a printing press. The first proof which shall be transferred as the first colour, is 30 then covered over on those portions, which shall be printed in the second colour, while on the second proof which shall be reprinted in the second colour, all those portions are covered over, which serve to print 35 the first colour. The first proof being covered over as described is now turned over or reversed on a suitable transfer material. The same is done with the second colour proof on another transfer material. From 40 each of these materials a right side up proof is made on a separate zinc or aluminum plate and the plates, being prepared in a well-known manner, are then mounted on the respective plate cylinder.

45 In practising this novel method of providing plates for single or multicolour offset printing I prefer using a printing machine by means of which not only this process can be carried out in a very simple manner, but 50 which will also serve for printing from the plates in the manner aforesaid.

In practical operation the printing plates are obtained in the following manner: A sheet of paper is fixed on the printing cylinder of an offset printing press, preferably 55 of the novel type which will be described

more specifically hereinafter, and I operate this press so as to produce a print on the sheet from the printing forme. The right side up proof thus obtained is directly transferred onto the rubber cylinder of the offset printing press in right to left reversal and is reproduced right side up on the printing plate contacting with the rubber cylinder. Instead of transferring the right side up proof first obtained onto the rubber cylinder, I may also replace the printing forme from 60 which this proof has been taken, by a rubber plate, onto which this proof is then transferred by causing the rubber plate to move 65 in contact with the proof lying on the printing cylinder, and from this rubber plate the right to left print is then transferred right side up onto a printing plate mounted onto a plate cylinder adapted to rotate in contact 70 with the rubber plate.

The printing press which allows practising the novel process, and which is preferably of the cylinder high speed press type, has mounted against the impression cylinder a transfer member, preferably the well known rubber cylinder, which is adapted to transfer from the impression cylinder onto the plate cylinder and vice versa. There is further provided a rubber plate adapted to reciprocate below and in contact with the impression cylinder, and this rubber plate can be replaced by a printing forme. Above the rubber plate is mounted a second plate cylinder, both this and the rubber cylinder 80 are adapted to be thrown out of operation separately. The operator is at leisure to use in the transferring of the proof onto a printing plate either the rubber cylinder or the rubber plate or both of them.

85 In the drawings affixed to this specification and forming part thereof, a device embodying my invention is illustrated diagrammatically by way of example.

90 In the drawings

Fig. 1 is an elevation partly in vertical section of a cylinder printing machine embodying my invention, while

Fig. 2 illustrates a detail.

95 Referring to the drawings, *a* is the impression cylinder, *b* the rubber cylinder mounted to run against it, and *c* the zinc plate or similar cylinder which cooperates with the cylinder *b*. *d* is the bedplate and the rubber surface removably arranged 100 thereon, and *e* is the zincplate or similar cylinder mounted above the bedplate.

As shown in Fig. 2 plate cylinder *e* has its journals *e*¹ mounted in an eccentric *e*² arranged for rotation in bearings and carrying an arm *e*³ the free end of which is connected with a hand lever *e*⁴ by means of a link *e*⁵. A bar *e*⁶ extends between the points of connection of the arms *e*³ and links *e*⁵ on either side of the machine thereby allowing the eccentrics *e*² on either side of the plate cylinder *e* to be turned by means of a single handle *e*⁴. A similar arrangement is provided for throwing out plate cylinder *c* and rubber cylinder *b*.

The necessary transfers on the plate cylinders *c* and *e* for the preparation of the offset printing, are obtained according to this invention in the following manner:

After the type or printing forme has been arranged in the proper size, and with the proper registration, for example on the bed-plate *d*, a proof is taken therefrom on a suitable paper which is fixed on the impression cylinder *a*. This proof is a positive or right-sided one. By simply allowing it to pass through the machine, the right-sided proof is turned over or reversed on the rubber cylinder *b* and transferred therefrom right side up to the plate of the plate cylinder *c*. After the usual preparation of the plate and after the type forme at *d* has been removed the printing can be effected at once by means of the cylinders *c*, *b*, *a*, a one-colour offset print being thus obtained.

If plates are to be made for use in two-colour offset printing, two proofs are made from the type or printing forme. The first proof which shall be transferred as the first colour is covered over on those portions which shall be printed in the second colour while conversely, on the second proof, which shall be printed in the second colour, those portions are covered over which serve to print the first colour. The first proof is now transferred in the manner just described onto the plate cylinder *c*, while the second proof, after the substitution of the type forme on the bed plate *d* by the rubber surface, is transferred to the plate of the plate cylinder *e* by simply allowing it to run through the machine rear side upwards onto the rubber plate, from which it passes right side up onto the plate cylinder *e*. After the plates have thus been prepared and finished, printing may commence at once.

Printing is now proceeded with in the following manner, assuming two-colour work printing on one side to be produced:

The sheet which is seized in the usual manner by the grippers (not shown) of the impression cylinder *a* is printed in its first colour by the rubber cylinder *b* and in its second colour on its passage between the impression cylinder *a* and the bedplate *d* by the rubber surface mounted on this latter and which has received the proof or offset

from the plate cylinder *e*. If the second colour is to be produced in book printing instead of in offset printing, the bedplate *d* is provided with a book printing forme instead of the rubber surface, this forme being inked in the ordinary way without coming into contact with the plate cylinder *e*. If on the other hand the cylinder *e* be thrown out of operation, simple offset printing can be produced by means of the cylinders *b* and *c*, in which case the machine is preferably run more rapidly. In like manner the machine can be used as a simple high speed book printing press after the offset printing mechanism *c*, *b* and the cylinder *e* have been put out of operation and an ordinary book printing forme inserted in the bed plate *d*.

In this way a very accurate registration of the plates in two-colour offset printing, and an extremely rapid reproduction of the printing plates for offset printing, is ensured, without any other auxiliary machines being required.

I wish it to be understood that I do not desire to be limited to the exact details of construction shown and described, for obvious modifications will occur to a person skilled in the art.

I claim:

1. Cylinder printing machine comprising a frame, an impression cylinder rotatably supported in said frame, a plate cylinder and a rubber cylinder rotatably supported in said frame, said rubber cylinder being inserted between said impression cylinder and said plate cylinder and adapted to transfer one colour from said plate cylinder onto said impression cylinder, a rubber plate mounted for reciprocation and contacting with said impression cylinder and means for depositing another colour on said rubber plate.

2. Cylinder printing machine comprising a frame, an impression cylinder rotatably supported in said frame, a plate cylinder and a rubber cylinder rotatably supported in said frame, said rubber cylinder being inserted between said impression cylinder and said plate cylinder and adapted to transfer one colour from said plate cylinder onto a sheet lying on said impression cylinder, a rubber plate removably mounted for reciprocation and contacting with the sheet on said impression cylinder and means for depositing another colour on said rubber plate.

3. Cylinder printing machine comprising a frame, an impression cylinder rotatably supported in said frame, a plate cylinder and a rubber cylinder rotatably supported in said frame, said rubber cylinder being inserted between said impression cylinder and said plate cylinder and adapted to transfer one colour from said plate cylinder onto said impression cylinder, a rubber plate mounted for reciprocation and contacting with said impression cylinder and means for depositing another colour on said rubber plate.

with said impression cylinder and a second plate cylinder for depositing another colour on said rubber plate.

4. Cylinder printing machine comprising a frame, an impression cylinder rotatably supported in said frame, a plate cylinder and a rubber cylinder rotatably supported in said frame, said rubber cylinder being inserted between said impression cylinder and said plate cylinder and adapted to transfer one colour from said plate cylinder onto said impression cylinder, a rubber plate mounted for reciprocation and contacting with said impression cylinder and, 15 a second plate cylinder for depositing another colour on said rubber plate said second plate cylinder being arranged to be thrown out.

5. Cylinder printing machine comprising a frame, an impression cylinder rotatably supported in said frame, a plate cylinder and a rubber cylinder rotatably supported in said frame, said rubber cylinder being inserted between said impression cylinder and 20 said plate cylinder and adapted to transfer one colour from said plate cylinder onto said impression cylinder, a rubber plate removably mounted for reciprocation and contacting with said impression cylinder and, a 25 second plate cylinder for depositing another colour on said rubber plate, said second plate cylinder being arranged to be thrown out.

6. Cylinder printing machine comprising a frame, an impression cylinder rotatably supported in said frame, a plate cylinder and a rubber cylinder rotatably supported in said frame, said rubber cylinder being inserted between said impression cylinder and said plate cylinder and adapted to

transfer one colour from said plate cylinder 40 onto said impression cylinder, said rubber cylinder being arranged to be thrown out, a rubber plate mounted for reciprocation and contacting with said impression cylinder and means for depositing another colour on 45 said rubber plate.

7. Cylinder printing machine comprising a frame, an impression cylinder rotatably supported in said frame, a plate cylinder and a rubber cylinder rotatably supported 50 in said frame, said rubber cylinder being inserted between said impression cylinder and said plate cylinder and adapted to transfer the one from said plate cylinder onto said impression cylinder, a rubber plate 55 mounted for reciprocation and contacting with said impression cylinder and, a second plate cylinder for depositing another colour on said rubber plate said rubber cylinder and said second plate cylinder being ar- 60 ranged to be thrown out.

8. Cylinder printing machine comprising a frame, a plate cylinder and a rubber cylinder rotatably supported in said frame, said rubber cylinder being inserted 65 between said impression cylinder and said plate cylinder and adapted to transfer one colour from said plate cylinder onto said impression cylinder, a rubber plate removably mounted for reciprocating and contacting with a sheet lying on said impression cylinder, and a second plate cylinder 70 for depositing another colour on said rubber plate, said rubber cylinder and said second plate cylinder being arranged to be 75 thrown out.

In testimony whereof I affix my signature.
HERMAN BIELEFELDT.
